BRAKE OPERATING MECHANISM

Charles J. Keim, Oil City, Pa., assignor to United States Steel Company, a corporation of New Jersey

Application December 29, 1949, Serial No. 135,598

6 Claims. (Cl. 188—77)

1

This invention relates to improvements in brake operating mechanisms, particularly for hoist reel brakes which have compound leverage systems.

An object of the invention is to provide improved brake operating mechanisms which are of the compound leverage type but which have fewer parts and are of simpler construction than previous mechanisms with which I am familiar.

A further object of the invention is to provide improved brake operating mechanisms which can be removed or installed as a unit and which include an integral supporting assembly of base plate, bearings, pivot ears and equalizer bracket, thus assuring that the parts always are aligned properly.

A further object of the invention is to provide improved brake operating mechanisms which are of the compound leverage type and yet employ only a single operating shaft and also eliminate at least one of the levers usually employed for each brake band.

In accomplishing these and other objects of the invention, I have provided improved details of structure, a preferred form of which is shown in the accompanying drawings, in which:

Figure 1 is a side elevational view of a hoist which is equipped with a brake operating mechanism embodying features of the present invention;

Figure 2 is a vertical sectional view taken substantially on line II—II of Figure 1;

Figure 3 is a vertical sectional view taken substantially on line III—III of Figure 2;

Figure 4 is a vertical sectional view taken substantially on line IV—IV of Figure 3;

Figure 5 is a vertical sectional view taken substantially on line V—V of Figure 4;

Figure 6 is an end elevational view of the integral supporting assembly for the brake operating mechanism;

Figure 7 is a top plan view of the supporting assembly; and

Figure 8 is a side elevational view of the supporting assembly taken substantially on line VIII—VIII of Figure 6.

The drawings show a hoist which in the present instance is embodied in well drilling drawworks. The hoist comprises a fixed foundation 10, a hoist reel 12 and in this instance a sand reel 13. The hoist reel has a brake drum 14 and a similar brake drum at the opposite end, and brake bands 15 and 15a which surround said drums. Rollers 16, 16a and 17, a spring 18 and a set screw 19 position brake band 15 in relation to drum 14 in the usual way, and similar elements,

2

not shown, position brake band 15a. The sand reel has a brake drum 20 and a similar drum on the opposite end and brake bands 21 and 21a.

In accordance with the present invention, the 5 brake operating mechanism comprises an integral supporting assembly which includes a base plate 22, a bearing 23, a first pair of spaced pivot ears 24, a second pair of spaced pivot ears 24a, a bearing 25 fixed to one of the ears 24, a bearing 10 25a fixed to one of ears 24a and an equalizer bracket 26 (Figures 6, 7 and 8). Said assembly 15 preferably is of welded construction. The bearings, ears and equalizer mounting are positioned accurately and, since the assembly is integral, the parts never can become misaligned. A plurality of bolts 27 removably attach said supporting assembly to foundation 16 (Figures 2 and 3).

Bearings 23, 25 and 25a are axially aligned and rotatably mount a brake lever shaft 28, which 20 is the only shaft needed in this mechanism. The pivot ears which do not carry bearings are apertured for passage of said shaft. The shaft carries a brake operating lever 29, which is keyed thereto to turn the shaft. The base plate assembly 25 can include the usual quadrant 30, and the brake operating lever can be equipped with the usual friction grip 31 for locking the mechanism. Crank arms 32 and 32a are fixed to shaft 28 and extend upwardly and rearwardly (Figure 30). Ears 24 and 24a carry pivot pins 33 and 33a, respectively, which preferably are fixed to these ears. Brake band 15, pivot pin 33 and crank arm 32 are in alignment and likewise brake band 15a, pivot pin 33a and crank arm 32a. Pivot pin 33 carries a lever 34 and pivot pin 33a carries a similar lever which extend downwardly and forwardly. A link 35 connects the extremities of crank arm 32 and lever 34 and a similar link connects the extremities of crank arm 32a and the other lever. The live ends of the brake bands are 35 pivotally connected to these same levers between the pivot pins and the links, as indicated at 36.

An equalizer 37 is pivoted to equalizer bracket 26 on a pivot pin 38 (Figure 2). Links 39 and 39a 40 connect the dead ends of the brake bands and the ends of said equalizer, which thus anchors these dead ends. The equalizer bracket can have sockets 40 and 40a which receive springs 41 and 41a for cushioning the equalizer, and to retain the 45 equalizer in a central position when brake is released to assure equal release action on both bands.

A sand reel brake lever 42 conveniently can be 50 mounted to turn concentrically with shaft 28 on a bearing sleeve 43 which extends inwardly from

bearing 23 (Figures 4 and 7). A linkage 44 connects this brake lever with the sand reel brake band (Figure 1). This arrangement enables an operator to control both brakes from a single station.

In operation, rotation of shaft 28 and operating lever 29 clockwise, as viewed in Figures 1 and 3, applies the brake and rotation counter-clockwise releases the brake. Within the operating limits, clockwise rotation constantly shortens the lever arm between crank arm 32 and link 35, constantly lengthens the lever arm between said link and lever 34, and constantly shortens the lever arm between said lever and the live end of brake band 15. The relation of the lever arms on the opposite side for applying brake band 15a is the same. Therefore, the farther the brake operating lever moves clockwise, the greater the mechanical advantage of the force which is applied to the brake bands. The operating mechanism of the present invention furnishes this movement with only a single shaft and only one crank arm, link and lever for each brake band.

The brake operating mechanism can be removed as a unit from the hoist. It is necessary only to disconnect the live end of brake band 15 from lever 34 at 36, similarly disconnect the live end of brake band 15a from its lever, disconnect either equalizer 37 from its bracket 26 or disconnect the links between the dead ends of the bands and the equalizer, and to remove bolts 27. The unitary construction of the brake operating mechanism thus simplifies dismantling and reassembling the hoist and the integral construction of the supporting assembly always assures that the parts are aligned properly.

From the foregoing description, it is seen that the brake operating mechanism of the present invention accomplishes a compound leverage with fewer parts than usual, facilitates assembling or dismantling the hoist, and always assures that the parts are aligned properly.

While I have shown and described only a single embodiment of the invention, it is apparent that modifications may arise. Therefore, I do not wish to be limited to the disclosure set forth but only by the scope of the appended claims.

I claim:

1. In a hoist having a fixed foundation, a hoist reel rotatably supported on said foundation, a pair of brake drums, one of which is at each end of said reel, and a pair of brake bands, one of which surrounds each of said drums, a brake operating mechanism comprising a base plate removably attached to said foundation, pivot ears and axially aligned bearings integral with said base plate, a brake lever shaft rotatably mounted in said bearings, an operating lever fixed to said shaft, a pair of upwardly and rearwardly extending crank arms fixed to said shaft, a pair of pivot pins carried by said pivot ears, the brake band, pivot pin and crank arm of each pair being in alignment, a pair of downwardly and forwardly extending levers, one of which is carried for pivotal movement by each of said pivot pins, links connecting the extremities of said crank arms and of said last named levers, the live ends of said brake bands being connected to said last named levers between said pivot pins and said links, and equalizer means anchoring the dead ends of said brake bands, said operating mechanism being removable as a unit from the hoist.

2. In a hoist having a fixed foundation, a hoist reel rotatably supported on said foundation, a pair of brake drums, one of which is at each

end of said reel, and a pair of brake bands, one of which surrounds each of said drums, a brake operating mechanism comprising a base plate removably attached to said foundation, pivot ears, axially aligned bearings and an equalizer bracket integral with said base plate, a brake lever shaft rotatably mounted in said bearings, an operating lever fixed to said shaft, a pair of crank arms fixed to said shaft, a pair of pivot pins carried by said pivot ears, the brake band, pivot pin and crank arm of each pair being in alignment, levers carried for pivotal movement by said pivot pins, links connecting the extremities of said crank arms and of said last named levers, the live ends of said brake bands being connected to said last named levers between said pivot pins and said links, an equalizer carried by said equalizer bracket, and means connecting the dead ends of said brake bands and said equalizer.

3. In a hoist having a fixed foundation, a hoist reel rotatably supported on said foundation, a pair of brake drums, one of which is at each end of said reel, and a pair of brake bands, one of which surrounds each of said drums, a brake operating mechanism comprising a base plate removably attached to said foundation, pivot ears, axially aligned bearings and an equalizer bracket integral with said base plate, a brake lever shaft rotatably mounted in said bearings, an operating lever fixed to said shaft, a pair of upwardly and rearwardly extending crank arms fixed to said shaft, a pair of pivot pins carried by said pivot ears, the brake band, pivot pin and crank arm of each pair being in alignment, a pair of downwardly and forwardly extending levers, one of which is carried for pivotal movement by each of said pivot pins, links connecting the extremities of said crank arms and of said last named levers, the live ends of the brake bands being connected to said last named levers between said pivot pins and said links, an equalizer carried by said equalizer bracket, and means connecting the dead ends of said brake bands and said equalizer, said brake operating mechanism being removable as a unit from the hoist.

4. A unitary operating mechanism for hoist drum brakes comprising a base plate adapted to be attached to a hoist foundation, pivot ears and axially aligned bearings integral with said base plate, a brake lever shaft rotatably mounted in said bearings, an operating lever fixed to said shaft, a pair of upwardly and rearwardly extending crank arms fixed to said shaft, a pair of pivot pins carried by said pivot ears, a pair of downwardly and forwardly extending levers, one of which is carried for pivotal movement by each of said pivot pins, links connecting the extremities of said crank arms and of said last named levers, means on said last named levers between said pivot pins and said links for connecting the live ends of a pair of brake bands, and means for anchoring the dead ends of the bands.

5. A unitary operating mechanism for hoist drum brakes comprising a base plate adapted to be attached to a hoist foundation, pivot ears, axially aligned bearings, and an equalizer bracket integral with said base plate, a brake lever shaft rotatably mounted in said bearings, an operating lever fixed to said shaft, a pair of upwardly and rearwardly extending crank arms fixed to said shaft, a pair of pivot pins carried by said pivot ears, a pair of downwardly and forwardly extending levers, one of which is carried for pivotal movement by each of said pivot pins, links con-

necting the extremities of said crank arms and of said last named levers, means on said last named levers between said pivot pins and said links for connecting the live ends of a pair of brake bands, and an equalizer carried by said equalizer bracket adapted to anchor the dead ends of the brake bands.

6. An integral supporting assembly for hoist reel brake operating mechanisms comprising a base plate, two pairs of spaced pivot ears upstanding from said base plate, a bearing upstanding from said base plate, a bearing carried by one pivot ear of each pair, the other pivot ears being apertured, said bearings and the apertures

5 being axially aligned, and an equalizer bracket upstanding from said base plate.
